DUPLEX SHAPER

Alton J. Wells, Bell, Calif.

Application April 16, 1934, Serial No. 720,784

15 Claims.

(Cl. 90—38)

My invention relates generally to metal cutting machinery and more particularly to a duplex shaper and the principal object of my invention is, to provide a shaper having a ram and operating parts therefor that may be quickly and conveniently shifted so as to operate in either a horizontal or vertical plane as desired in order that the one machine may be utilized for both vertical and horizontal cutting and shaping operations.

Further objects of my invention are, to provide a duplex shaper wherein the bed plate that carries the bed and ram is hinged to the cross slide so that said bed plate and the ram carried thereby may be conveniently swung from horizontal to vertical positions and vice versa, to provide relatively simple and convenient braces between the cross slide and the bed plate for firmly holding the same in vertical position or at any angle between horizontal and several degrees past vertical in order that the shaper may be conveniently employed in operations incident to the production of dies, taper keys, key ways and the like.

Further objects of my invention are, to provide simple and efficient means for controlling the movements of the ram, to provide an improved form of clutch and reverse mechanism for operating the ram, to provide spring cushioning means for absorbing the shocks and vibration developed in the ram driving mechanism and further, to provide simple and efficient means for counterbalancing the weight of the ram while the same is operating in a vertical position.

A further object of my invention is, to provide a duplex shaper that is directly driven by an electric motor, which motor is suitably mounted on the hinged bed plate and to provide simple and efficient driving connections between the motor and the main driving shaft of the shaper.

Further objects of my invention are, to provide improved means for effecting vertical adjustment of the table of the shaper and to provide a relatively simple and efficient vise for engaging and holding the work upon the table.

With the foregoing and other objects in view, my invention consists in certain novel features of construction and arrangements of parts that will be hereinafter more fully described and claimed and illustrated in the accompanying drawings in which:

Fig. 1 is a side elevational view of my improved duplex shaper and showing the bed plate and ram in horizontal positions.

Fig. 2 is a vertical cross section taken on the line 2—2 of Fig. 1.

Fig. 2A is a vertical cross section taken on the line 2A—2A of Fig. 1.

Fig. 3 is a top plan view of the shaper.

Fig. 4 is a top plan view of the vise that is mounted on the work table.

Fig. 5 is a vertical longitudinal section taken on the line 5—5 of Fig. 4.

Fig. 6 is a cross section taken on the line 6—6 of Fig. 5.

Fig. 6A is an elevational view of a clamping block that is mounted for sliding movement on the fixed jaw of the device and which carries the movable jaw.

Fig. 6B is a rear elevational view of the clamping block seen in Fig. 6A.

Fig. 7 is a side elevational view of the shaper with the bed plate, bed and ram moved into vertical position.

Fig. 7A is a cross section on the line 7A—7A of Fig. 7.

Fig. 8 is a rear elevational view taken looking in the direction indicated by the arrow 8 in Fig. 7.

Fig. 9 is an enlarged elevational view with parts broken away and in section looking in the direction indicated by the arrow 9 in Fig. 7.

Fig. 10 is a cross section taken on the line 10—10 of Fig. 9.

Fig. 11 is a cross section taken on the line 11—11 of Fig. 10.

Fig. 12 is a cross section taken on the line 12—12 of Fig. 11.

Fig. 13 is an elevational view looking in the direction indicated by the arrow 13 in Fig. 11.

Fig. 14 is a cross section taken on the line 14—14 of Fig. 11.

Fig. 15 is a cross section taken on the line 15—15 of Fig. 13.

Fig. 16 is a cross section taken on the line 16—16 of Fig. 11.

Fig. 17 is a cross section taken on the line 17—17 of Fig. 9.

Fig. 18 is an elevational view partly in section taken on the line 18—18 of Fig. 9.

Fig. 19 is a sectional view similar to Fig. 11 and showing the driving connections between the motor shaft and the main driving shaft of the shaper.

Figs. 20 and 21 are perspective views of the co-operating parts that function on a shock absorber for counteracting the shocks and vibration in the clutch that controls the reverse movements of the ram.

Fig. 22 is a vertical section taken on the line 22—22 of Fig. 7.

Fig. 23 is a vertical section taken on the line 23—23 of Fig. 7.

Fig. 24 is a vertical cross section taken on the line 24—24 of Fig. 23.

5 Fig. 25 is an elevational view with parts in section of the ram counterbalancing means and showing the position thereof when the ram and bed are horizontally disposed.

10 Fig. 26 is a detail elevational view of a link that is located on the end of the cable forming a part of the ram counterbalancing means.

15 Referring by numerals to the accompanying drawings which illustrate a preferred embodiment of my invention, 10 designates the base 15 of the shaper which is a substantially box-like structure preferably of cast metal and secured on top of said base in any suitable manner is a cross slide base 11.

20 Mounted for transverse sliding movement on said cross slide base, is a cross slide 12 and connected by a suitable hinge 13 to the forward end of said cross slide, is a bed plate 14.

25 Adjustably mounted on the bed plate and retained in its adjusted position by means of bolts 15, is a bed 16 that serves as a support for the sliding ram.

30 The lower portions of the bolts 15 that secure the bed to the bed plate are adapted to occupy suitable notches 17 that are formed in the sides 30 of the bed plate and which arrangement enables the bed to be conveniently adjusted lengthwise upon the bed plate and firmly secured thereto after proper adjustment.

35 A nut 18 depends from cross slide 12 and receives a transversely arranged feed screw 19 that is intermittently rotated by conventional feed screw operating means designated generally by the numeral 20, Fig. 2.

40 By connecting the forward end of bed plate 14 to cross slide 12 by the hinge 13, said bed plate and parts carried thereby may be conveniently swung upward so as to occupy an inclined or vertical position and to firmly hold the bed plate in its inclined or vertical 45 position, a pair of braces 21 are arranged between said bed plate and cross slide, said braces being provided with coinciding longitudinally disposed slots 22 and the upper end of one of these braces is pivotally connected to 50 a bracket 23 that projects from the underside of the bed plate 14 and the lower end of the other brace is pivotally connected to a bracket 24 that projects outwardly and downwardly from the rear end of cross slide 12 (see Fig. 7).

55 A pair of plates 25 are applied to the outer faces of the braces 21, the upper and lower edges of which plates are provided with flanges 26 that project over the upper and lower edges of the braces and passing through said plates and 60 through the slots in the braces is a bolt 27, on the threaded end of which is seated a clamping nut 28, (see Fig. 7A).

65 The construction just described provides means for firmly holding the bed plate and parts carried thereby in vertical or inclined position and if desired the upper edges of the braces 21 may be provided with graduated scales for the purpose of determining the angular position in which the bed plate is held.

70 When the bed plate occupies a horizontal position the braces 21 occupy an out-of-the-way position to the rear of the base 10 as illustrated by dotted lines in Fig. 1.

75 Arranged for vertical sliding movement by the ways 30 that are mounted on the front side of base

10, is a plate 29 and projecting outwardly from the lower portion of the plate, is a table 31 which carries the work holding vise.

Detachably secured to the table top and depending therefrom, is a screw 32 that passes through a nut 33, the latter being seated in the upper end of a sleeve 34 and projecting from the lower portion of said sleeve is a hand wheel 35.

10 The lower portion of sleeve 34 is internally threaded for engagement with the externally 10 threaded surface of a tube 36, the lower end of the latter being rigidly seated in a base or foot 37 that projects from the lower front portion of base 10.

15 The construction just described and which is illustrated in Fig. 2A provides simple and efficient means for quickly raising and lowering the vise carrying table 31.

20 Screw 32 has a righthand thread and tube 36 a lefthand thread in order that when sleeve 34 20 is rotated a relatively quick movement will be imparted to table 31.

25 The work holding vise that is mounted on table 31 comprises a disc 38 that is suitably mounted for adjustment toward and away from the base 25 10 and adapted to be clamped to the table in adjusted position and mounted for rotation on said disc 38, is a disc 39.

30 A swivel bolt 40 passes through the centers of discs 38 and 39 and holds the disc 39 for rotation 30 on said disc 38 and also provides means for clamping said disc 39 to disc 38 in adjusted position.

35 Suitably secured on top of disc 39, is a plate 41 at one end of which is formed integral an up-standing stationary jaw 42.

40 Formed through the center of plate 41, is a longitudinally disposed slot 43 and secured to the underside of said plate, to the sides of said slot, are toothed rack plates 44.

45 Arranged for sliding movement on top of plate 41 and opposing the fixed jaw 42, is a sliding jaw 45 and arranged on the top thereof is a bearing block 46. This bearing block is pivotally connected to jaw 45 by bolt 47 that passes downward through the slot 43 in plate 41 and engages a 45 clamping plate 48, the ends of which latter bear against the lower ends of the teeth of the rack plates 44. This bolt 47 provides means for locking the adjustable jaw 45 to plate 43 as the adjustable jaw has engaged and clamped the work 50 against the fixed jaw.

55 Arranged for sliding movement on top of plate 41 to the rear of the sliding jaw 45, is a block 49, the upper portion of which is bifurcated for the reception of a nut 50, which nut is mounted for locking movement in said block by means of trunnions 51 that extend from said nut outwardly through the sides of said block.

60 Depending from block 49 is a web 52 that passes through slot 43 and projecting forwardly from the lower end of said web, is a plate 53.

65 Projecting upwardly from the forward portion of plate 53, are teeth 54 that are adapted to engage between the teeth of rack plates 44.

70 The lower forward corner of block 49 is beveled as indicated by 55 and the upper rear corner of plate 53 is correspondingly beveled as designated by 56 in order that block 49 may be tilted slightly while positioned on plate 43 so as to disengage the teeth 54 from the teeth of rack plate 44.

75 Such construction permits ready adjustment of the block 49 toward and away from the movable jaw.

76 Passing horizontally through nut 50, is a screw 57, the forward rounded end of which engages in

a recess that is formed in the rear face of bearing block 46.

Arranged for reciprocating movement upon bed 16, is a ram 58 and carried by the forward end 5 thereof is a conventional tool holder designated generally by the numeral 59, Figs. 1 and 7.

Ram 58 is provided with a longitudinally disposed slot 60 and arranged on the upper face of said ram on one side of this slot is a rack bar 61 10 having outwardly presented teeth.

Secured to the end portions of the ram on the opposite side of slot 60 from rack bar 61 and spaced apart from the body of the ram, is a rack bar 62 having inwardly presented teeth.

15 The means for counterbalancing the ram while the same is operating in a vertical position and which is illustrated in Figs. 22 to 26 will now be described.

Secured to the rear end of bed 16 is a plate 63 20 and mounted for rotation on the upper face of said plate is a housing 64 provided in its periphery with worm wheel teeth 65.

25 Journaled in antifriction bearings in the centers of plate 63 and housing 64, is a shaft 66 and carried by the upper end of said shaft is a drum 67.

Secured to this drum is one end of a steel cable 68 that is arranged to wind onto and from said drum and the opposite end of said cable carries a 30 plate 69 provided in its center portion with a key-hole opening 70 and in its forward end with an aperture 71.

When the ram is operating in a vertical position, the keyhole opening 70 in plate 69 engages a 35 headed stud 72 that projects downwardly from the forward portion of the ram and when the latter is operating in a horizontal position, said key-hole opening engages a headed stud 73 that projects upwardly from the forward portion of 40 bed 16.

The aperture 71 in the forward end of plate 69 is adapted to receive the hooked end of a rod that is utilized for shifting plate 69 from stud 72 to stud 73 and vice versa.

45 The inner end of a spiral spring 74 is secured to shaft 66 and the outer end is secured to the drum of housing 64.

The tension of spring 74 is sufficient to counterbalance the weight of the ram while the same 50 is operating in a vertical position and to vary the tension of said spring, the drum or housing 64 is rotated by means of a worm 75 that is formed on a shaft 76 and the latter being journaled in suitable bearings on top of plate 63. Worm 75 engages the worm wheel teeth 65 on drum 64 and shaft 76 is rotated by means of a crank handle 77 55 on one end of said shaft.

The means for driving the ram will now be described.

60 Rigidly secured by means of a bracket 78 to the side of bed 16, and on the opposite side of the shaper from the feed screw operating mechanism 20, is an electric motor 79, the shaft of which carries a worm 80 that meshes with a worm wheel 81. A sleeve 82 is mounted for both rotary and longitudinal movement upon a main driving shaft 83 and said sleeve slides through worm wheel 81.

This shaft is journaled for rotation in anti-friction bearings 84 that are arranged in bearing 70 supporting blocks 85 and the latter being secured to bed 16.

The inner end of sleeve 82 carries a flange 86 and projecting from said flange, are pins 87 that are adapted to enter apertures 88 that are formed 75 in the adjacent face of worm wheel 81.

Worm wheel 81 is provided with a hub 89 and keyed thereto, is a pinion 90 that meshes with a pinion 91 and the latter being journaled for rotation on a stud 92 that is seated in a bracket 93.

Rigidly fixed to pinion 91, is a slightly larger 5 pinion 94.

Keyed to the outer end of sleeve 82, is a pinion 95 that is smaller than pinion 90 and this pinion 95 is adapted to mesh with pinion 94 when sleeve 82 is moved inward upon shaft 83 so as to disengage the pins 87 from the apertures 88.

Formed integral with the outer side face of pinion 95 is a pair of diametrically opposite articulate lugs 96 and which lugs are positioned in notches 97 that are formed in a disc 98.

15 The length of the notches 97 is greater than the width of the lugs 96 and seated in recesses 99 that are formed in disc 98 at one end of each recess, are expansive coil springs 100 that bear against the adjacent faces of the lugs 96 on 20 pinion 95.

The construction just described provides means for absorbing and counteracting the shock and vibration incident to the engagement of the clutch with the pinions that transmit motion from the 25 driving shaft to the racks on the ram.

The end of driving shaft 83 that projects from sleeve 82 through disc 98 is made square or non-circular in cross section as designated by 101 and a corresponding square or non-circular opening 30 102 is formed in disc 98 for the accommodation of this portion of the shaft.

Secured to the end of the lugs 96 that project from pinion 95, is the inner end of a short handle 103, which latter is utilized for imparting sliding 35 movement to the sleeve 82 and this handle projects through a suitable housing 104 that encloses the speed control mechanism just described.

When the handle 103 is pulled outward to its 40 limit of movement to engage pins 87 in apertures 88 in worm wheel 81, the motion of the motor shaft is transmitted from worm 80 to worm wheel 81, thence to and through sleeve 82 and thence through pinion 95 and disc 98 to the main driving shaft 83, which shaft has the non-circular end 45 101 that passes through the corresponding opening 102 in disc 98.

Under such conditions and with the parts as 50 illustrated in Fig. 9, the shaft 83 is being driven at relatively slow speed.

In order to drive shaft 83 at increased speed, handle 103 is pushed inward as illustrated in Figs. 10 and 11 so as to disengage pins 87 from the apertures 88 and as sleeve 82 is moved inward the teeth of pinion 95 will engage the teeth of 55 pinion 94 which latter is larger in diameter than pinion 95 and also larger than pinion 91 that is driven by pinion 90 that is secured to the hub of worm wheel 81.

Under such conditions the motion from the 60 motor shaft delivered to worm wheel 81 will be transmitted by pinion 90 to pinion 91, thence to larger pinion 94, thence to smaller pinion 95 and from the latter through disc 98 to the shaft 83 and due to the relative sizes of the pinions the 65 driving shaft will be rotated at relatively high speed.

Handle 103 is yieldingly retained at both ends of its sliding movement upon shaft 83 by a spring 70 pressed pin 103^a that is carried by disc 98 and which pin is adapted to enter either one of a pair of spaced indentations 103^b that are formed in one of the flat faces on the end of shaft 83.

Loosely mounted on main driving shaft 83 and meshing with the teeth of rack 61, is a pinion 75

105 that imparts forward travel to the ram and formed on one side of this pinion, is a clutch face 106, preferably teeth.

Loosely mounted on shaft 83 and spaced apart from pinion 105, is a pinion 107 of larger diameter and the face of which pinion is of double width and provided with two sets of teeth 108 and 109.

The teeth 108 mesh with the teeth of rack 62 and in operation, imparts reverse motion to the ram.

Formed on the inner face of this larger pinion 107, is a clutch face 110, preferably teeth.

Arranged for sliding movement upon shaft 83 between the ram driving pinions 105 and 107 and held to rotate therewith, preferably by means of a key, is a sleeve clutch 111 provided at one end with a clutch face 112 that is adapted to engage clutch face 106 on pinion 105 and at the opposite end the sleeve is provided with a clutch face 113 that is adapted to engage the clutch face 110 on pinion 107.

Formed on the intermediate portion of the sleeve 111, are spaced flanges 114.

The means for automatically shifting the clutch to bring about reverse movement of the ram and which is illustrated in detail in Figs. 9, 10, and 17 will now be described.

Secured to the front face of one of the bearing supporting blocks 85 and at a point directly over the main driving shaft, is a plate 115 and arranged for sliding movement thereupon, parallel with the axis of the driving shaft, is a plate 116.

Seated in the sliding plate and projecting through a slot 117 in fixed plate 115, is a pin 118 and mounted for rotation on the rear or lower end thereof, is a roller 119 that is positioned between the flanges 114 of clutch 111.

Fulcrumed upon a stud 120 that is seated in plate 115, is the inner end of a lever 121 that extends laterally directly across the outer face of rack 62 and beyond said rack the outer portion of this lever is bent upwardly and outwardly as designated by 122.

Formed in the intermediate portion of lever 121, is an inclined slot 123 in which is positioned a roller 124 that is carried by pin 118.

Fulcrumed upon stud 120 and overlying lever 121 is a lever 125 in the central portion of which is formed an inclined slot 126 that is positioned directly over slot 123 in lever 121.

A short arm 127 overlies lever 125 at one end of said arm overlying slot 126 and mounted for rotation on a hub that extends inwardly from said arm into the slot 126, is a roller 128.

The end of arm 127 and roller 128 are provided with a short slot 129 that is slightly inclined with respect to the axis of said arm for the accommodation of the forward or upper end of pin 118.

The edges of arm 127 that project toward the stud 120 are provided with teeth 130 and meshing therewith are the toothed ends 131 of short arms 132 and which latter are fulcrumed upon pins 133 that are seated in fixed plate 115.

Projecting from the free ends of these arms 13 are pins 134 and connecting said last mentioned pins, is a retractile coil spring 135.

The free end of lever 125 is substantially wider than the underlying lever 121 and projecting from lever 121, through a short arcuate slot 136 that is formed in the wide end of lever 125, which slot is concentric with the axis 120, is a pin 137.

Adjustably mounted upon rack 62 on opposite sides of the levers 121 and 125, are blocks 138 which during the reciprocating movements of the ram alternately engage opposite edges of the

lever 125 so as to automatically operate the clutch actuating means just described.

These contact blocks 138 are retained in their adjusted positions on rack 62 by set screws 139.

To engage lever 121 and hold the same and the clutch in neutral position so as to stop the operation of the ram, a plate 140 is arranged for sliding movement on the righthand one of the bearing blocks 85 and formed in the forward end of this plate is a notch 141 of sufficient width 10 to engage the upwardly bent portion 122 of lever 121.

An expansive spring 142, positioned in a slot in this plate, tends to move the same forwardly into engagement with lever 121 and positioned in 15 said slot to the rear of said spring, is a sliding block 143, from which projects a pin 144. This pin projects through a slot 145 in a cover plate 146 that overlies sliding plate 140 and said pin also passes through an inclined slot 147 that is 20 formed in a lever 148. The inner end of this lever is fulcrumed on a stud 149 that is seated in cover plate 146.

The mechanism just described provides means whereby, at any time during the backward and forward movements of the ram, the lever 121 may be engaged in neutral position to hold the clutch actuating mechanism and the clutch itself, in neutral positions, thereby controlling the starting and stopping of the ram.

With lever 148 in the position illustrated in Fig. 9, the plate 140 is at its rearward limit of movement with the lug at one side of the notch 142 bearing against the bent end of lever 121.

By shifting lever 148 upon its fulcrum, pin 144 35 travels through slot 147, thereby moving block 143 forwardly to compress spring 142 and when lever 121 moves to a neutral position during its subsequent clutch shifting operation plate 140 will be moved outward under the influence of 40 spring 142 so that the bent end of lever 122 will occupy notch 141 and thus be held in neutral position.

The means for imparting movement from main drive shaft 83 to the feed screw 19 is illustrated 45 in Figs. 7, 8, and 11 to 16 inclusive and will now be described.

This driving mechanism includes a pinion 150 that is secured to a shaft 151, the latter being journaled in a sleeve 152 and said sleeve in turn 50 being journaled in an eccentric 153. This eccentric is mounted in the main crank shaft bearing 85 on the righthand side of the shaper.

Seated in the eccentric 153 and projecting outwardly through a slot 154 in bearing 85 is a short 55 arm 155 which when shifted from one end of the slot to the other partially rotates the eccentric and moves shaft 151 and pinion 150 carried thereby so that the latter is moved into or out of engagement with the teeth 109 of the double width 60 gear wheel or pinion 107.

Thus the manipulation of arm 155 controls the operation of the feed screw operating means.

Formed integral with the outer end of sleeve 152, is a disc 156, in which are seated the threaded 65 ends of screws 157, which latter pass through apertures formed in a disc 158, the latter being substantially thicker than the disc 156.

Interposed between the heads of screws 157 and shoulders 159, at the lower ends of the 70 recesses that are occupied by the screws, are expansive coil springs 160.

Such construction permits disc 158 to move away from disc 156 and such movement is yieldingly resisted by the springs 160.

Formed in the outer face of disc 158 is a T-slot 161 that receives the head of a stud 162 and mounted on the projecting shank of this stud, is a collar 163.

5 Journalled on this collar is one end of a rod 164 that is retained in position by a nut 165 on the threaded end of bolt 162 and the lower end of this rod is pivotally connected to a crank arm 166. This crank arm is mounted to slide 10 upon and rotate with a shaft 167 that is journaled in bearings 168 on cross slide base 11 and said shaft passes through a bearing 169 that depends from cross slide 12.

Crank arm 166 is maintained in position adjacent to the bearing 168a on the cross slide, by a finger 169 that is secured to the bearing and which engages in a groove 170 that is formed in the hub of the crank arm.

Secured to shaft 167 is a short depending crank 20 arm 171 that is connected by a link 172 to the oscillating arm of the lever of the feed screw operating mechanism 20.

Formed in the inner face of disc 158 concentric with shaft 151, is a circular chamber 173 and occupying this chamber is a disc 174 that is keyed to shaft 151. The periphery of this disc is provided with teeth.

Interposed between the side faces of discs 174 and the inner faces of discs 156 and 158, are friction producing discs 175 or fiber or analogous material.

30 A block 176 is arranged for sliding movement in an opening in disc 158 that communicates with the chamber 173 and formed on the inner end of this disc is a tooth 177 that is adapted to engage between the teeth on the periphery of disc 174.

Block 176 is normally forced inwardly under the influence of expansive coil springs 178, which 40 are arranged between said block and a plate 179, that is secured to disc 158 and which overlies the opening that is occupied by said block.

Mounted on a stud that projects from the side of block 176 through a short radial slot 180 that 45 is formed in disc 156, is a roller 181 that engages the surface of a cam 182 that is supported upon the hub of eccentric 162 and which hub is concentric with shaft 151 and sleeve 152.

The surface of this cam that is engaged by 50 roller 181 is approximately 180° in length and the greater portion thereof is concentric with the axis of shaft 151 as designated by 183.

At both ends of the concentric cam surface 183, the surface inclines or raises slightly as designated by 184 and at the ends of these inclined portions are shoulders 185 that function as stops to limit the movement of roller 181.

It is necessary to shift the position of the discs 156 and 158 when the shaper is shifted from horizontal to vertical position and vice versa in order to bring the slot 161 into proper position for transmitting movement to the feed screw and likewise it is necessary to change the position of the cam 182 when the position of the discs is 65 changed.

Formed in the edge of cam disc 182 between the ends of the cam surface 183, are notches 186 that are disposed 90° apart and adapted to engage in either one of these notches is the outer 70 end of a pin 187 that is mounted for sliding movement in the bearing 85 and which is normally moved outward under the influence of a spring 188. This cam latching pin 187 is shifted rearwardly out of engagement with the notch in 75 the cam disc by means of a pin 189 that pro-

jects from the outer portion of pin 187 through a slot 190 that is formed in bearing 85.

Thus the cam may be readily shifted to correspond with the position of the discs 156 and 158 when the machine is being operated either horizontally or vertically and said cam is firmly retained in its shifted positions by the latching pin 187.

Assuming that the ram is being operated in a horizontal position, the bed plate rests on the 10 cross slide and bed 16 is firmly anchored to the bed plate by the bolts 15.

Fig. 1 shows the shaper and the operating parts thereof in position for horizontal movement of the ram.

The work is clamped between the fixed and movable jaws 42 and 45 of the vise and the movable jaw is locked against the work by tightening bolt 47.

The vise supporting table 31 is adjusted vertically by manipulation of the hand wheel 35 and by employing the nut 33 and threaded rod 32, the table may be very quickly raised or lowered to the desired position.

When the work has been properly positioned 25 and the tool carried by the tool holder 59 at the forward end of the ram has been properly adjusted motor 79 is started and worm 89 on the motor shaft transmits rotary motion to worm wheel 81.

When handle 103 is pulled outward to engage pins 87 in the recesses 88 as illustrated in Fig. 19, worm wheel 81 will drive sleeve 82 and pinion 95 which is keyed to said sleeve will drive disc 98 which latter is mounted on the non-circular 35 portion 101 of main driving shaft 83, thereby imparting rotary motion to said shaft.

If it is desired to operate main driving shaft 83 at increased speed, handle 103 is moved inward to the position illustrated in Figs. 10 and 40 11, thereby disengaging pins 87 from the recesses 88 and pinion 90 carried by the hub of worm wheel 81 now drives pinions 91 and 94 and the latter drives pinion 95 which in turn drives disc 98 and thereby imparts rotary motion at increased speed to the main driving shaft.

As the main driving shaft is rotated, clutch 111 will be rotated inasmuch as it is connected by a key to the driving shaft and at both ends of the travel of the ram, the clutch will be moved 50 lengthwise upon the main driving shaft by the operation of certain parts illustrated in Figs. 9 and 10 and as a result of engagement of the blocks 138 on rail 62 with the edges of lever 125, thus bringing about a reversal of the movements 55 of the ram.

As illustrated in Fig. 10, the clutch is shown with its clutch face 112 in engagement with the clutch face on pinion 105 and the rotation of this pinion and its engagement with the teeth 60 of rack 61, moves the ram forwardly on its working stroke.

The rear one of the blocks 38 carried by rail 62 approaches and engages the rear edge of lever 125, thereby swinging said lever forward upon its axis, the stud 120, and as such movement takes place, the inclined edges of slot 126 against the roller 128 which roller is carried by the arm 130, said arm will be shifted lengthwise and thereby through the engagement of teeth 130 70 with the teeth 131 on the ends of arm 132, said arms will be swung on their axes, the studs 133 and the swinging apart of the outer ends of said arms 132 will expand retractile spring 135.

When the outer ends of the arms 132 move past 75

center or past a line intersecting the axes 133, the retraction of the expanded spring 135 will impart a quick snapping movement to arms 132 to move the same to their limit of movement and 5 the engagement of teeth 131 with the teeth on arm 130 will quickly impart further lengthwise movement to arm 127 so as to further swing lever 125 on its axis.

As lever 125 is thus moved the end of slot 136 10 will contact with pin 137 and the further movement of lever 125 will impart corresponding movement to lever 121.

The engagement of the edges of inclined slot 123 in lever 121 with roller 124 that is carried 15 by pin 118 will impart short longitudinal movement to said pin and to the sliding plate 116 in which said pin is seated and roller 119 that is carried by the upper end of said pin 118 engaging the clutch 111 between the flanges 114 20 will shift said sleeve lengthwise upon the main driving shaft so as to disengage clutch face 112 from the clutch face on pinion 105 and engage clutch face 113 with the clutch face 110 on pinion 108.

25 Inasmuch as pinion 108 engages the teeth on rack bar 62 and this rack bar is reversely positioned with respect to rack bar 61, the ram will be caused to reverse its movement and move rearwardly upon the bed 16.

30 As the ram approaches its rearward limit of movement, the forward one of the blocks 138 will engage the front edge of lever 125, thereby bringing about a reversal of the movements just described and following the shifting of the clutch 35 on the main driving shaft and the engagement of said clutch with pinion 105 the ram will be caused to move forward on its working stroke.

In order to engage lever 121 and hold same in a neutral position so as to maintain clutch 111 40 in neutral position, the operator engages lever 148 and swings same rearwardly after the ram is operating in a horizontal position or downwardly after the ram is operating in a vertical position and the engagement of pin 144 in the 45 inclined slot 147, will move block 143 forwardly through slot in plate 140, thereby compressing spring 142 and as lever 121 is moved into a neutral position by one of the blocks 138, the plate 140 will be forced forward by the power stored 50 in spring 142 so that the downwardly bent portion 122 of lever 121 will be engaged in the notch 141 in the inner end of said plate and thus said lever 121 is held in a neutral position and likewise clutch 111 is maintained in a neutral position 55 and the ram will cease to operate.

When it is desired to start the ram, the position of lever 148 is reversed so that the same occupies the position illustrated in Fig. 9 and the engagement of pin 144 in slot 147 moves 60 block 143 rearwardly in the slot in plate 140 and moves the latter plate outward so as to release or disengage lever 121 from the notch 141 and under the influence of spring 127 the parts of the clutch shifting mechanism will swing to 65 one position or the other and thereby cause the ram to resume its reciprocating movements.

Each time the ram moves rearward or on its reverse stroke, the teeth 109 on pinion 107, which latter is driven by clutch 111, will impart rotary 70 motion to pinion 150 that is keyed to shaft 151 and this motion will be transmitted to disc 174 having the notched periphery, which disc is keyed to shaft 151.

As a result of the engagement of tooth 177 75 carried by sliding plate 176 with the teeth of

disc 174, the head comprising discs 156 and 158 will be rotated and through rod 164 that is connected to the head by bolt 162 motion will be imparted to the said screw 19, thereby shifting the cross slide laterally a short distance from 5 the cross slide base 11 in the conventional manner.

When the ram is operating in a horizontal plane, the rear end of rod 164 is connected to crank arm 166 as illustrated in Fig. 1 and when 10 the ram is operating in a vertical position, it is necessary to utilize an extension rod between said rod 164 and crank arm 166 as illustrated in Fig. 7.

As rod 164 moves crank arm 166, shaft 167 15 will be partially rotated, thereby imparting movement to crank arm 171 and link 172 and which latter is connected to the conventional feed screw operating mechanism.

During the reciprocating movements of the ram, roller 181 that is carried by sliding plate 156, rides 20 on the concentric face 183 of disc 182 and as the roller approaches the ends of its travel, it rides up the inclined surfaces 184 and then comes to rest against one of the shoulders 185. As the roller rides up one of the inclined surfaces 184, 25 sliding plate 156 will be moved a short distance radially outward so as to disengage tooth 177 from the teeth of disc 174, thereby permitting said disc, which is keyed to shaft 151, to continue to rotate with said shaft while the ram is moving to the 30 end of its stroke.

It will be understood that the feed screw operating mechanism just described is actuated to rotate the feed screw to feed the cross slide upon its base during the reverse or rearward movement of 35 the ram and that during the forward or working stroke of the ram the head comprising the discs 156 and 158 and parts carried thereby are reversely rotated by the engagement of the teeth 109 on pinion 107 with the teeth of pinion 40 150 during which time the plate 176 is held at its outer limit of movement by the engagement of the roller 181 on one of the inclined faces 184 so that tooth 177 is out of engagement with the teeth of disc 174. 45

In order to cause the head comprising the discs 156 and 158 to be picked up and caused to rotate with toothed disc 174 that is fixed to shaft 151 as the ram reverses its movements at the ends of its stroke and while the roller 181 is resting on one of the shoulders 185 with the tooth 177 out of engagement with the teeth of disc 174, the friction discs 175 are interposed between the discs 156 and 158 and the side faces of disc 174. These discs 175 under the pressure of springs 160 provide sufficient friction between the head and the disc 174 to cause the parts to rotate together at the beginning of each stroke of the ram and thereby carry the roller 181 away from the shoulder and down the inclined surface 184 until tooth 177 is engaged 55 with the teeth of disc 174, thereby providing a positive driving connection between the head and disc 174.

The engagement of latch pin 187 in the notches 186 affords means for holding the head comprising the discs 156 and 158 in proper position while the ram is being operated in either horizontal or vertical position.

In order to render the feed screw operating mechanism inoperative, pin 155 is engaged and 70 moved through slot 154 approximately a quarter turn, thereby rotating the eccentric 153 so as to shift the position of shaft 151 so that pinion 150 is out of engagement with the teeth 109 on disc 107. 75

- Thus it will be seen that I have provided a shaper having a ram mounted so that it may be swung from horizontal to vertical positions in order to accomplish various metal shaping and cutting operations and which shaper is relatively simple in construction, capable of being easily and quickly shifted from one position to another and which is very effective in performing the functions for which it is intended.
- 10 It will be understood that minor changes in the size, form and construction of the various parts of my improved duplex shaper may be made and substituted for those herein shown and described without departing from the spirit of the 15 invention, the scope of which is set forth in the appended claims.

I claim as my invention:

1. In a duplex shaper the combination with a base, of a work table mounted for vertical adjustment on the front of said base, a cross slide base, a cross slide mounted for transverse movement on said cross slide base, a bed plate hinged to the forward portion of said cross slide so as to swing upwardly and forwardly therefrom, a bed 25 mounted for longitudinal adjustment on said bed plate, a ram mounted for reciprocatory movement on said bed and means for counterbalancing the weight of the ram when the same occupies a substantially vertical position.
- 30 2. In a duplex shaper the combination with a base, of a work table mounted for vertical adjustment on the front of said base, a cross slide base, a cross slide mounted for transverse movement on said cross slide base, a bed plate hinged to the 35 forward portion of said cross slide so as to swing upwardly and forwardly therefrom, a bed mounted for longitudinal adjustment on said bed plate, a ram mounted for reciprocatory movement on said bed, means including a spring for counter- 40 balancing the weight of the ram while the same is operating in a substantially vertical position and means for adjusting the tension of said spring.
3. In a duplex shaper, a bed, a ram mounted for reciprocatory movement on said bed, a shaft journaled on said bed, driving connections between 45 said shaft and said ram, a motor mounted on said bed, a worm carried by the shaft of the motor, a sleeve loosely mounted on one end of the ram operating shaft, a worm wheel loosely mounted on 50 said sleeve, which worm wheel is engaged by the worm on the motor shaft, projections carried by said sleeve for engaging in recesses in said worm wheel to effect driving engagement between said sleeve and worm wheel, a pinion secured to said 55 sleeve, a disc mounted to rotate with and slide lengthwise upon the ram operating shaft, said disc and pinion having engaging parts which permits slight relative rotary movement between said disc and pinion and springs arranged between the 60 interengaging parts of said pinion and disc for yieldingly resisting the relative rotary movement between said parts in one direction.
4. In a duplex shaper, a bed, a ram mounted for reciprocatory movement on said bed, a shaft 65 journaled on said bed, driving connections between said shaft and said ram, a motor mounted on said bed, a worm carried by the shaft of the motor, a sleeve loosely mounted on one end of the ram operating shaft, a worm wheel loosely mounted on 70 said sleeve, which worm wheel is engaged by the worm on the motor shaft, projections carried by said sleeve for engaging in recesses in said worm wheel to effect driving engagement between said sleeve and worm wheel, a pinion secured to said sleeve, a disc mounted 75

to rotate with and slide lengthwise upon the ram operating shaft, said disc and pinion having engaging parts which permits slight relative rotary movement between said disc and pinion, springs arranged between the interengaging parts 5 of said pinion and disc for yieldingly resisting the relative rotary movement between said parts in one direction, a pinion carried by said worm wheel, which pinion is larger than the pinion carried by the sleeve, a pair of connected different 10 sized pinions with which the pinion on the sleeve and the pinion on the worm wheel are adapted to engage and a handle connected to said sleeve for moving the same lengthwise upon the ram operating shaft.

5. In a duplex shaper the combination with a base, of a cross slide mounted for transverse movement on said base, a bed hinged to said cross slide so as to swing upwardly and forwardly through an arc of at least 90°, a ram mounted for reciprocatory movement upon said bed, a driving shaft mounted for operation on said bed, a motor carried by the bed for driving said shaft, reversely arranged racks on the ram, pinions loosely mounted on the driving shaft for engaging the 25 teeth of said racks, a clutch mounted to slide lengthwise upon and rotate with said driving shaft between said pinions, the ends of which clutch are adapted to engage and drive said pinion, a pair of cooperating springheld levers for 30 imparting sliding movement to said clutch and means mounted on one of the rack bars for engaging said levers at the ends of the travel of the ram to actuate said clutch and effect a reversal of the driving movement imparted to said ram. 35

6. In a duplex shaper the combination with a base, of a cross slide mounted for transverse movement on said base, a bed hinged to said cross slide so as to swing upwardly and forwardly through an arc of at least 90°, a ram mounted 40 for reciprocatory movement upon said bed, a driving shaft mounted for operation on said bed, a motor carried by the bed for driving said shaft, reversely arranged racks on the ram, pinions loosely mounted on the driving shaft for engaging the teeth of said racks, a clutch mounted to slide lengthwise upon and rotate with said driving shaft between said pinions, the ends of which clutch are adapted to engage and drive said pinions, a pair of cooperating springheld levers for 45 imparting sliding movement to said clutch, means mounted on one of the rack bars for engaging said levers at the ends of the travel of the ram to actuate said clutch and effect a reversal of the driving movement imparted to said ram and 50 manually operable means for engaging one of the clutch operating levers and holding same in neutral position.

7. In a duplex shaper, a bed, a ram mounted for reciprocatory movement upon said bed, a driving shaft mounted for operation on said bed, a motor carried by the bed for driving said shaft, reversely arranged racks on the ram, pinions loosely mounted on the driving shaft for engaging the teeth of said racks, a clutch mounted to 65 slide lengthwise upon and rotate with said driving shaft between said pinions, the ends of which clutch are adapted to engage and drive said pinions, a pair of cooperating levers for imparting sliding movement to said clutch, means mounted on one of the rack bars for engaging said levers at the ends of the travel of the ram to actuate 70 said clutch and effect a reversal of the driving movement imparted to said ram, manually operable means for engaging one of the clutch 75

operating levers and holding same in neutral position and spring actuated means associated with said levers for shifting the same out of neutral position when said levers are released from said 5 manually operating holding means.

8. In a duplex shaper, a cross slide base, a cross slide mounted for movement upon said base, a feed screw mounted on said base for imparting movement to said cross slide, a bed plate carried 10 by said cross slide, a ram mounted for reciprocatory movement on said bed plate, a driving shaft journaled on said bed, means actuated by said driving shaft for imparting reciprocatory movement to said ram, means actuated by said driving shaft for intermittently rotating said feed screw and manually operable means for rendering said feed screw actuating means inoperative.

9. In a duplex shaper, a cross slide base, a cross slide mounted for movement upon said base, a 20 feed screw mounted on said base for imparting movement to said cross slide, a bed plate carried by said cross slide, a ram mounted for reciprocatory movement on said bed plate, a driving shaft journaled on said bed, means actuated by 25 said driving shaft for imparting reciprocatory movement to said ram, a shaft journaled on the bed of the ram adjacent to said driving shaft, driving connections between said driving shaft and second mentioned shaft, driving connections 30 between said second mentioned shaft and the cross slide feed screw and manually operable means for disengaging the driving connections from said driving shaft to said second mentioned shaft.

35 10. In a duplex shaper, a base, a table mounted for vertical adjustment on the front of said base, means for raising and lowering said table, a work engaging vise adjustably mounted on said table, a cross slide base carried by said base, a cross slide mounted for operation upon said cross 40 slide base, a feed screw for imparting movement to said cross slide, a bed plate hinged to said cross slide, a bed carried by said bed plate, a ram mounted for reciprocatory movement on 45 said bed, a main driving shaft journaled on said bed, means for converting the rotary motion of said driving shaft to reciprocating motion and imparting the same to said ram, means for varying the speed of the motion transmitted from 50 said driving shaft to said ram, means for rendering the ram driving means inoperative and means for transmitting motion from the main driving shaft to the cross slide feed screw.

11. In a duplex shaper, the combination with 55 a base, of a cross slide mounted for transverse movement on said base, a bed plate hinged to the front side portion of said cross slide so as to swing upwardly and forwardly through an arc of at least 90°, adjustable braces between said bed 60 plate and cross slide for holding the bed plate

in differently adjusted positions, a ram mounted for reciprocatory movement on said bed plate, a motor carried by said bed plate and means actuated by said motor for imparting reciprocatory movement to said ram. 5

12. In a duplex shaper, the combination with a base, of a cross slide mounted for transverse movement on said base, a bed plate hinged to the front side portion of said cross slide so as to swing upwardly and forwardly through an arc of 10 at least 90°, adjustable braces between said bed plate and cross slide for holding the bed plate in differently adjusted positions, a ram mounted for reciprocatory movement on said bed plate, a motor carried by said bed plate, means actuated 15 by said motor for imparting reciprocatory movement to said ram and means for controlling the reciprocating movement of said ram.

13. In a duplex shaper, the combination with a base, of a cross slide mounted for transverse 20 movement on said base, a bed plate hinged to the front side portion said cross slide so as to swing upwardly and forwardly through an arc of at least 90°, adjustable braces between said bed plate and cross slide for holding the bed plate 25 in differently adjusted positions, a ram mounted for reciprocatory movement on said bed plate, a motor carried by said bed plate, means actuated by said motor for imparting reciprocatory movement to said ram and automatically operating 30 means for causing the ram to reverse its motion at the ends of its travel.

14. In a duplex shaper, the combination with a base, of a cross slide mounted for transverse movement on said base, a bed plate hinged to 35 the front side portion of said cross slide so as to swing upwardly and forwardly through an arc of at least 90°, adjustable braces between said bed plate and cross slide for holding the bed plate in differently adjusted positions, a ram mounted 40 for reciprocatory movement on said bed plate, a motor carried by said bed plate, means actuated by said motor for imparting reciprocatory movement to said ram and a work supporting table adjustably mounted on the forward por- 45 tion of said base.

15. In a duplex shaper, the combination with a base, of a cross slide mounted for transverse movement on said base, a bed plate hinged to the front side portion of said cross slide so as to 50 swing upwardly and forwardly through an arc of at least 90°, adjustable braces between said bed plate and cross slide for holding the bed plate in differently adjusted positions, a ram mounted for reciprocatory movement on said bed plate, a 55 motor carried by said bed plate, means actuated by said motor for imparting reciprocatory movement to said ram and means for supporting said base plate in a substantially vertical position.

ALTON J. WELLS. 60
